APPARATUS FOR SHAPING SHEETS

John H. Engel, Escondido, Calif.

Application September 22, 1944, Serial No. 555,339

13 Claims. (Cl. 153—48)

1

This invention relates to apparatus for shaping heavy metallic sheets.

The principal object of the invention is to provide an efficient means for shaping or bending large heavy metal plates, such as those commonly employed in the construction of welded steel ships and large aircraft, and to provide such a means whereby the heavy sheets, plates or shapes may be handled and shaped with comparative ease considering their great size and weight.

The handling of heavy metal plates of the character indicated has heretofore usually offered considerable difficulty and the means employed for conducting the bending operations have not been conducive to convenient handling, nor have such means been conducive to sufficiently rapid and accurate shaping, especially of long plates.

Therefore, it is a further object of my invention to provide equipment by which large heavy sheets may be conveniently moved relative to appropriate shaping dies, such equipment including a structure carrying the shaping dies which structure in itself is adjustable to accommodate its position to changing curvature in the sheet as the sheet is shaped.

A further object is to provide means for rocking a die-supporting carriage about a shaping die means as a center whereby to accommodate a bent or curved portion of a plate moving into a passage provided in the carriage for the shaped portion after it has passed the die means.

A further object is to provide an elongated reciprocable die means actuated at high velocity, whereby a long plate may be rapidly curved throughout its entire length on any given line.

Another object is to provide means for converting reciprocating motion of relatively long stroke, i. e. oscillating motion of relatively great amplitude, into vibratory motion of relatively very small amplitude. A further object is to provide for variation in the rate of reciprocation whereby to vary the vibratory motion and the power of the resultant blows. A variable speed motor may be employed for this purpose, or air or steam driven devices.

It is also an object of the invention to provide means for dampening the great volume of objectionable sound and vibrations incident to operation of a striking die. In one form, this is accomplished by devices pressing against the plate being shaped which may also act at the same time as guides.

The invention includes other objects and features which will be apparent from the following disclosure to those skilled in the art. Other

such features are the methods herein disclosed of shaping a sheet by the described vibratory striking motion of small amplitude; so shaping a long sheet throughout its length; and continuously moving the sheet past the shaping means.

In the accompanying drawings one embodiment of my invention is shown merely by way of illustration. In these drawings,

Fig. 1 is principally an end elevation of an apparatus constructed according to the present invention, portions being shown in vertical section;

Fig. 2 is chiefly a plan view taken approximately from the line 2—2 of Fig. 1;

Fig. 3 is a front elevation as indicated by the line 3—3 of Fig. 1, parts being broken away;

Fig. 4 is a cross-sectional detail through the shaping dies employed.

According to the apparatus illustrated in the drawings, an overhead framework 10 is employed for the purpose of supporting an elongated heavy metal sheet or plate 12 in vertical position in order that it may be raised and lowered between two opposing parts of a die mechanism D by which it is to be shaped. The plate 12 is suspended in operative position from the framework 10 through an I-beam 13 secured thereto and supporting wheeled carriages 14 of conventional construction. From each carriage 14 there is suspended a reversible electric motor 15 supporting an elevating device including for example a block 16 and cable 17. Each elevating device carries suitable means 18 for engaging the upper end of the plate 12, the means 18 being illustrated as an elongated split sleeve which receives the upper edge of the plate 12, the latter being provided with any appropriate cooperating supporting means 19.

The die mechanism D and operating means therefor are carried upon a large supporting structure or carriage 20 large enough to be adapted to the maximum size of plates to be handled, such carriage 20 being relatively high and relatively long, and the die mechanism D being correspondingly long.

The carriage structure 20 shown is provided with a curved bottom 21 which constitutes a supporting wall for the carriage and is in the form of a segment of an elongated cylinder whose center of curvature is located at the operative center of the die mechanism D. The supporting bottom wall 21 of the carriage structure 20 is rockingly carried by a plurality of pairs or series of heavy rollers 22 engaging tracks 23 of the bottom 21, the rollers 22 being mounted upon a

plurality of transverse heavy beams 24 secured in the bottom of a concrete cellar 25 which extends the length of the carriage 20 and in which the lower portion of the carriage 20 is positioned. Brackets 26 having ears 28 in which the rollers 22 are trunnioned at 29 are secured to the beams 24 and thereby position the rollers 22 and the curved bottom 21 of the carriage 20.

The curved bottom 21 of the carriage 20 supports a front wall 30, a plurality of vertical transverse end and intermediate walls 31, floors 32 extending between the transverse walls 31, and a rear wall 33, the floors 32 extending also from the front wall 30 to the rear wall 33. The various walls, the bottom 21 and the floors 32 are secured together by welding, riveting or bolting to form a unitary whole. Intermediate their edges, the transverse walls 31 are provided with large openings 34 which, as shown, extend from a point in each wall 31 adjacent the corresponding floor 32 upward to the top of said transverse walls 31, at which points the opening 34 is reduced to leave a narrow space between the two resultant vertically disposed sections of each wall 31. Along the tops of the sections of the walls 31 at the right of the structure, as seen in Fig. 1, there is welded a bed plate 35, and along the tops of the vertical sections of the walls 31, as seen at the left of Fig. 1, is welded a similar bed plate 35a, the bed plates 35 and 35a being respectively welded also to the rear wall 33 and the front wall 30. The bed plates 35 and 35a serve to support the parts of the die mechanism D.

Extending rearwardly from the rear wall 33 and in line with the bed plate 35 is a platform 36 whose forward edge is welded to the top of the rear wall 33. This platform 36 is relatively narrow and extends rearward from the middle of the carriage 20, as best seen in Fig. 2. Bracket plates 37 whose inner ends are welded to the rear wall 33 of the carriage 20 act as supports for the platform 36, and a rear plate 38 is secured to the rear ends of the plates 37 and to the rear end of the platform 36 to impart rigidity.

For the purpose of rocking the carriage 20 upon the rollers 22, a jack screw 40, pivotally connected at 42 to one of the bracket plates 37, is provided, a lower portion of the jack screw 40 passing through a jack nut 43 threaded thereon. The jack nut 43 is rotatably secured on a swinging support 44 pivotally connected at 45 to one of the I-beams 24. A beveled gear 46, rigidly connected with the jack nut 43, engages a beveled gear 48 adapted to be driven by a reversible motor 49. The motor 49 may be operated to rotate the jack nut 43 to draw the lower end of the jack screw 40 downward into a pit 50 below the adjacent portion of the corresponding I-beam 24, whereby to lower the rear end of the carriage 20 including the platform 36 and its brackets 37, as indicated by the lower set of broken lines as seen at the right of Fig. 1. The motor 49 also may be operated to extend the jack screw 40 above the jack nut 43 and raise the rear portion of the carriage 20 into the upper broken line position as seen at the right of Fig. 1. In this manner, the curved bottom wall 21 is made to roll upon the rollers 22 and cause the carriage 20 to rock about the operative center of the die mechanism D.

The die mechanism D, which is carried upon the bed plates 35 and 35a, comprises a bifurcated striking or hammering die 54 and a counter die 55, as best shown in Fig. 4, these dies being elongated to conform with elongation of the carriage 20 and the elongated plate 12 to be shaped.

The counter die 55 is carried against a resilient cushion 56, in an elongated slot in an otherwise cylindrical die member 58 which is mounted in the adjacent edge of a die holder 59 provided with a seat 60 which is formed on the arc of a circle. The seat 60 permits the counter die 55 to be adjusted with relation to the striking die 54 by rotation of the die member 58. Adjustment of the counter die 55 is maintained by means of a clamping plate 62 secured to the die holder 59 as by means of screws 63. The die holder 59 is retained upon a base plate 64 in any suitable manner, as by being welded to a wide I-beam 65 secured to an elongated bar 66 as by means of screws or bolts 68, the bar 66 being welded to the base plate 64 which is in turn welded to the bed 35a, if preferred; or all of these parts may be secured to the bed 35a by the bolts 68.

The striking die 54 is similarly mounted upon a striking-die holder and hammer 70 having in its forward edge a seat 72 to receive the striking die 54, preferably in a non-rotatable manner by reason of non-circular configuration, the die 54 being bound to the die holder 70 by means of a flat bar 73 secured to the holder 70 by means of a plurality of screws 74. The striking die 54, the retaining bar 73, and the forward edge of the die holder 70 are elongated to conform with the elongation of the carriage 20 and with elongated plates 12 to be shaped.

The die holder 70 is adapted to be reciprocated in a direction from front to rear, and for this purpose travels upon a plurality of short tracks 75, the die holder 70 being guided on the tracks by depending portions 70a which lie between the tracks 75 and engage the edges thereof. As shown, the tracks 75 are in the form of I-beams.

The rear edge of the elongated die holder or hammer 70 is tapered from each end toward the middle, as best seen in Fig. 2, to form a narrow projecting neck 76 by means of which the holder 70 is reciprocated. The neck 76 rests upon a web 77 of a channeled guide 78 having upstanding guide flanges 79 between which the neck 76 reciprocates. The neck 76 is provided with ears 80 which overhang the flanges 79 and to each of which there is pivoted at 81 a link 82 which is in turn pivotally connected at 84 to the adjacent end of the main leaf 85 of a semi-elliptical bow spring including auxiliary leaves 86.

The middle portion of the resultant bow spring structure is bound to a yoke 88 through the medium of a die plate 89 secured to the spring structure by U-bolts 90. The neck of the yoke 88 is positioned in a guide plate 91 and has pivotally connected therewith at 92 an operating link 93 pivotally connected at 94 with an eccentric 95 keyed to a shaft 96 which passes through the platform 36 for driving connection with a pulley 98 through the medium of a suitable clutch mechanism 100. The clutch 100 is adapted to be actuated by a bell crank 102 carried upon a supporting bracket 103 and operated by means of any appropriate type of flexible cable 104. The pulley 98 is driven by a plurality of belts 105 from a variable speed motor 106 actuating a drive pulley 107. The motor 106 is carried by a shelf 108 secured to the rear plate 38 and supported by bracket plates 109.

In order to provide a supplemental device for controlling the position of the carriage 20, a cable 110 may be detachably connected with the

edge of the shelf 108 as through the medium of a suitably supported eye 111 to which is connected a hook 112 carried by a pulley 113 through which the cable 110 extends. The cable 110 is adapted to be operated for raising or lowering the rear portion of the carriage 20 by means of a reversible motor 114 suitably suspended from the overhead framework 10.

When a suspended metal plate 12 disposed between the dies 54 and 55 of the die mechanism is being acted upon by the die 54, it is desirable to care for the objectionable volume of noise produced by the hammer effect of the die 54 under influence of the reciprocating mechanism. This is in part accomplished by means of a dampening mechanism which comprises a plurality of rollers 115 or similar contacting devices of shock absorbing capacity which are carried by bifurcated arms 116 pivoted at 118 to an elongated bar 119 secured to the adjacent bed plate 35 through the medium of rearwardly extending arms 120 secured at 122 to appropriate supports 124 carried by the bed plate 35. The rollers 115 act also as guides.

The rollers 115 are adapted to be moved into contact against the plate 12 being shaped, and to be withdrawn therefrom when the plate is removed. This operation is accomplished through the medium of a connecting strip 125 to which each of the roller-carrying arms 116 is pivoted at 126. Each arm 116 adjacent the rearwardly projecting arms 120 is provided with an extension 116a which is under the influence of a contraction spring 128 secured to a fixed support 129, whereby the corresponding rollers 115 are pressed against the plate 12 and the strip 125 acts through the pivotal connections 126 to cause the remaining rollers 115 to press against the plate 12. When it is desired to withdraw the rollers 115 from contact with the plate 12, the arms 116 are actuated by means of a rock arm 130 which is secured to the roller-carrying arm 116 pivoted adjacent one of the arms 120 supporting the bar 119.

The rocker arm 130 is adapted to be actuated through the medium of any desirable flexible cable means 132. Additional dampeners 128 are desirably disposed within the carriage 20 at a short distance below the bed plate 35, these dampeners being also in the form of suitable rollers 128, or the like, which are carried upon brackets 129 fixedly or adjustably secured to the under side of the bed plate 35, as may be preferred. Thus, when a plate 12 is in position between the shaping dies 54 and 55 a portion of the great volume of noise otherwise produced by the hammering operation of the die 54 and the hammer 70 is overcome by reason of the pressure of the dampening rollers 115 and 128 against the plate 12.

For actuation of the various mechanisms which are required to be controlled by an operator, a platform 135 is mounted upon supporting posts 136 disposed one side of the rear platform 36 and extending from a suitable foundation up to the overhead framework 10. Upon the platform 135, an appropriate operating lever 138 is provided which is connected with the cable 132 that leads to the dampening devices 115 on the elongated bar 119. By actuating the lever 138 to provide draft upon the cable 132, the rollers 115 are withdrawn from the plate 12, or they are withdrawn from a corresponding position, so that the plate 12 may be either removed or introduced between the dies 54 and 55. Also mounted upon the platform 135 is a lever 140 connected with the cable

104 for actuation of the bell crank 102 to control the clutch 100 and thereby control the operation of the eccentric 95 by the electric motor 106, or to control valves, for example, in the case of air or steam actuation.

In addition to the controls 138 and 140, a switch 142 is conveniently suspended adjacent the operator's position for control of the reversible motors 15 by which the plate 12 is raised and lowered. Similarly, a switch 144 is suspended adjacent the operator's position to control the reversible electric motor 114 by which the cable 110 is actuated for raising and lowering the rear portion of the carriage 20. Conveniently placed upon one of the posts 136 is a control 145 for the reversible motor 49 which actuates the jack nut 48 upon the jack screw 40 for raising and lowering the rear end of the carriage 20. Also mounted on one of the posts 136 is a control 146 for the variable speed motor 106.

Operation

In preparing to shape a steel plate or other metal plate 12, the apparatus is placed in the general position shown in Fig. 1, the plate 12 being mounted in the split sleeve 18 with the aid of suitable retaining means 19 secured to the upper edge of the plate. The plate 12 is then lowered into position between the shaping dies 54 and 55 of the die mechanism D, by means of the hoist 16, the cable 17 and the reversible motors 15 which are controlled by the operator on the platform 135 through the medium of the depending switch 142. During the lowering of plate 12 into operating position, the dampeners 115 will have been withdrawn by the operator by retraction of the lever 138, which is released upon positioning of the lower edge of the plate 12 between the dies, thereby permitting the springs 128 to actuate the corresponding roller-supporting arms 116 and the connecting strip 125 to move all arms 116 and their rollers 115 into dampening position against the face of the plate 12 to be shaped.

Shaping is commenced by the operator's actuating the lever 140 to cause the bell crank 102 under influence of the cable 104 to actuate the clutch 100 so that the eccentric 95 is driven from the motor 106 through the medium of the pulley 98. The eccentric 95, through the medium of the link 93 and the reciprocating yoke 88, acts to reciprocate the bow spring 85, the stroke of the latter being the throw of the small crank arm which constitutes the eccentric 95.

The set of the bow spring 85 is such that its ends tend to move outwardly away from the neck 76 of the die holding hammer 70. After the spring 85 is moved toward the plate 12 which constitutes the work being operated upon, the effect is to swing the outer ends of the toggle links 82 toward the hammer 70 and contract the leaf springs 85 and 86 somewhat, after which the effect of the links 82 is to pull the neck 76 forward by reason of their connections at the pivots 81. The tendency of the reverse motion of the bow spring 85 as the yoke 88 is reciprocated is to pull the neck 76 and the hammer 70 away from the work. However, inertia of the long heavy hammer 70 offsets a large portion of the tendency of the bow spring 85 and the links 82 to move the hammer. The result is that, on a movement of the bow spring in one direction at the high rate of speed with which the yoke 88 is reciprocated, the movement of the spring overtakes the movement of the hammer 70 in the opposite direction. A result of this high rate of motion of the

bow spring 85 on its relatively long stroke imparted by the eccentric 95 is a very short stroke of the neck 76 and the hammer 70. Thus, where successive strokes of the bow spring 85 under the influence of the reciprocating mechanism may be considered an oscillatory movement of relatively great amplitude, successive strokes of the hammer 70 result in movements of very short amplitude so that the action of the hammer 70 upon the plate 12 being shaped is in the nature of a vibratory motion. By reducing the speed of the motor 106 through the control 146, the relative lag of the hammer or striking-die holder 70 may be reduced and the force of the blow may be changed.

Thus, the flexure of the bow spring 85 and the incidental swinging motion of the toggle links 82 to pull the hammer 70 first in one direction and then in the opposite direction results in a multitude of striking impulses in the form of strokes of extremely short amplitude but carrying substantially the full force of the power imparted both by the reciprocating mechanism and by the resilience of the spring 85. The effect is a hammering operation tending to curve the plate 12 into a shape as diagrammatically indicated by the broken lines in Fig. 4, there being, however, but an extremely small amount of actual movement of the hammer 70 and its striking die 54. The indicated curvature results by reason of the fact that the striking die 54 is bifurcated, as shown in Fig. 4, and cooperates with the relatively thinner counter die 55. Because the dies 54 and 55, the hammer 70 and die holder 59 for the die 55 are of a length corresponding with an elongated plate 12, the plate 12 may be curved throughout its entire length during a single operation.

Inasmuch as the plate 12 being shaped is relatively wide, the curvature which is gradually imparted requires the relatively wide passage through the carriage 20 represented by the openings 34 in the transverse vertical walls 31. This general position is indicated by broken lines in Fig. 1. As the amount of curvature becomes greater, such as indicated by the broken line curve in Fig. 4, a greater effective amount of space is required to accommodate the curved lower portion of the plate 12. To afford this accommodation, the operator causes the carriage 20 to be rocked by movement of the curved bottom 21 over the rollers 22 through operation of the reversible motor 49 to rotate the jack nut 43 in a corresponding direction for shortening the effective length of the jack screw 40. In this manner the opening 34 will be disposed at an angle to the position shown in Fig. 1, whereby to accommodate the lower edge of the curved plate. For the purpose of this adjustment, the operating cable 110 suspended from the motor 114 may either have been disconnected by disengagement of the hook 112 from the eye 111, or the operator may also have caused the motor 114 to extend the cable 110 by operating the control 144.

During the shaping operation above described, a part of the severe resounding noise imparted by engagement of the stroking die 54 with the plate 12 under influence of the vibration of the hammer 70 is overcome by means of the dampeners 115 and 128.

Having completed the bending required for the individual plate 12, the clutch 100 is actuated to disconnect the eccentric 95 from the motor 106 and stop the reciprocating mechanism. The operator then manipulates the control 142 to elevate the plate 12 from its position within the carriage 20, the dampening devices 115 having

been withdrawn by operation of the lever 138, as desired. The carriage 20 may be returned to the normal, full line position shown in Fig. 1 through actuation of the control 144 to operate the reversible motor 49 and lengthen the effective portion of the jack screw 40. The return of the carriage 20 to its normal, full line position may be accomplished after lifting plate 12 from the carriage 20, or simultaneously therewith, as best accommodates the curvature of the finished plate.

It will be understood that means such as disclosed may be arranged other than for operation upon sheets which are lowered vertically into position. For example, the sheets may be fed horizontally or at an acute angle to the vertical. Since many other modifications within the scope of the appended claims will be apparent to those skilled in the art, the disclosures hereof are to be considered merely as illustrative and not as limitative of the generic invention presented.

I claim as my invention:

1. In combination in plate-shaping apparatus: an elongated carriage; an elongated counter-die 25 mounted on said carriage; an elongated striking die mounted on said carriage in opposition to said counter-die, there being an upwardly directed passage between said dies and through said carriage adapted to receive an elongated plate to be shaped; and means to lower an elongated plate 30 and move said plate between said dies into said passage and both transversely and longitudinally thereof.

2. A combination according to claim 1 including means adapted to engage a plate positioned 35 between said dies to dampen sound vibrations produced by said striking die.

3. A combination according to claim 1 including movable means disposed adjacent said dies 40 adapted to engage a plate disposed between said dies to dampen sound vibrations produced by said dies.

4. A combination according to claim 1 wherein 45 said elongated striking die has a relatively narrow neck connected intermediate its ends, the combination including: means connected to said neck to actuate said striking die; means on said carriage to guide said neck; and means on said carriage to guide said striking die.

5. In combination in a shaping die mechanism: an elongated holder having in a forward edge a die-receiving pocket; a die member non-rotatably disposed in said pocket; means to bind said die member in said pocket; a second elongated die holder opposing the first mentioned die holder and having a pocket in an edge thereof formed on the arc of a circle; an elongated counter-die member rotatably mounted in the last named pocket; an elongated counter-die element 55 carried in a recess in said counter-die member; and means for binding said counter-die member in its pocket.

6. Plate-shaping apparatus comprising in combination: an elongated carriage having a curved bottom and a plurality of transverse vertical walls, each wall being provided with a wide opening leading to a relatively narrow entrance at the upper edge of said wall, each entrance being adapted to receive a plate being shaped and each 65 opening being adapted to accommodate a curved portion of said plate; rollers upon which said bottom rests and is adapted to roll; elongated die means disposed adjacent the entrances to the openings in said walls; means to present a plate to said die means for shaping; and means

to move said carriage on said rollers to adjust said openings to accommodate change in shape of a plate passing into said openings from said die means.

7. In combination in plate-shaping apparatus: an elongated carriage rockable about an axis, said carriage having a floor normally disposed in a substantially horizontal plane, said floor having an elongated passage therein parallel to said axis; means rockably supporting said carriage; elongated die means on said carriage to shape an elongated plate; means to lower the elongated plate to said die means and through said passage; and means to actuate said die means.

8. A combination as in claim 7 wherein said axis and said die means are located at said passage in said floor.

9. A combination as in claim 7 wherein said die means comprises opposing die members positioned at opposite sides of said passage, one of said die members being reciprocable in a substantially horizontal plane.

10. A combination as in claim 7 wherein said die means comprises opposing die members positioned at opposite sides of said passage, one of said die members being reciprocable in a substantially horizontal plane, said axis being disposed between said die members.

11. A combination as in claim 7 wherein said die means comprises opposing die members positioned at opposite sides of said passage, one of said die members being reciprocable in a substantially horizontal plane, said carriage providing an inner chamber to accommodate curved portions of the plate.

12. In combination in plate-shaping apparatus: a pair of opposed die means; a rockable carrier supporting said die means in a normally horizontal position; means to reciprocate one of said die means in such position; carrier means to suspend an elongated work piece between said die means, said rockable carrier being recessed to accommodate a lower portion of said work piece while suspended and as its shape is changed; and means

mounting said carrier for rocking of the latter as said shape changes.

13. In combination in a plate-shaping apparatus: base means; an elongated rockable carriage supported on said base means and adapted to be rocked thereupon about an axis, said carriage having an elongated passage therein parallel to said axis to receive both longitudinally and transversely an elongated plate to be shaped; elongated die means mounted on said carriage parallel to and disposed at said axis and adapted to shape said plate; support means on said base means and providing a mounting for said carriage for rocking of said carriage about said axis, said axis being located in said elongated passage at the locus of contact of said elongated die means with said plate; and means to actuate said die means for shaping said plate.
